UNITED STATES PATENT OFFICE.

JAMES M. DODGE, OF CHICAGO, ILLINOIS.

DOSE-MEASURING BOTTLE.

SPECIFICATION forming part of Letters Patent No. 236,997, dated January 25, 1881.

Application filed December 20, 1880. (No model.)

To all whom it may concern:

Be it known that I, JAMES MAPES DODGE, of Chicago, in the county of Cook and State of Illinois, have invented a new and useful 5 Dose-Measuring Bottle; and I do hereby declare that the following is a full and exact description thereof, reference being had to the accompanying drawings, making part of this specification.

10 My invention relates to a novel construction of bottle, adapted most particularly to contain liquid medicines, which have usually to be taken in prescribed doses or quantities, and designed to enable the user of the bottle and its 15 contents to measure and pour out only so much of the latter as may be prescribed, or as it may be desired to use at one time.

To this main end and object my invention consists in a bottle or receptacle for containing liquids provided with a measuring-receptacle, formed preferably in the neck of the bottle in such manner that by first tilting or turning the bottle so as to cause the liquid contents to flow into said auxiliary receptacle or measuring device, and then turning the bottle so as to leave a portion of the contents in said auxiliary receptacle, (and separated from the liquid in the main portion or chamber of the bottle,) the portion of the contents then contained 25 in said auxiliary receptacle may be poured out without discharging any portion of the contents of the main receptacle or body portion of the bottle, all as will be hereinafter more fully explained.

30 To enable those skilled in the art to make and use my invention, I will now proceed to more fully describe it, referring by letters to the accompanying drawings, forming part of this specification, and in which—

35 Figure 1 is a perspective view of a bottle embodying my invention. Fig. 2 is a longitudinal central section of the same, illustrating how the bottle should be manipulated to fill the measuring-receptacle; and Figs. 3 and 4 40 are similar sections with bottle in different positions, for purposes to be presently explained. Fig. 5 is a sectional view, showing a modified construction of bottle embracing my invention. Fig. 6 is a similar view, showing still another 45 modification of or another mode of carrying out my said invention.

Wherever the same part occurs in different

views it will be found designated by the same letter of reference.

In Figs. 1 to 4, inclusive, A is the main or 55 body portion of a bottle, and B what corresponds substantially to what is usually designated the "neck," but which I form, by preference, in a peculiar manner, and locate toward one side of the body portion A, instead of in 60 line with the center of the body portion, as is most commonly located the bottle-neck. At the extremity of the part B is the usual mouth or discharge-orifice, adapted to receive a cork or stopper, C, in the usual manner, and preferably formed with the ordinary circular flange or lip d.

The neck-like portion B, it will be observed, is suddenly and considerably enlarged or bulged out at one side immediately beyond the point 70 of its junction with the body portion A, so as to form, when the bottle shall be held in a certain position, as shown, for instance, at Fig. 3, a sort of hollow or receptacle, e, designed to hold a given or prescribed quantity of the 75 liquid contents of the bottle.

The conformation of this neck-like portion of the bottle, or its receptacle e, is such that the latter constitutes a sort of measuring-chamber—that is, this bulged portion or chamber e is designed and sized so as to contain the prescribed dose or quantity of the liquid to be used when the bottle shall be held in such a position (see, for instance, Fig. 3) that the liquid contents shall be separately held in 85 the main portion A and in the said receptacle e, and with the latter in a condition to permit the removal of the cork or stopper without spilling any of the contents of e. To thus supply the auxiliary chamber e the bottle should 90 be turned nearly or partially upside down, as shown, for instance, at Fig. 2, and then sufficiently righted to bring it into about the position seen at Fig. 3, (and its contents into the separated condition shown by the broken lines 95 in said figure,) and in the great majority of cases in which such a contrivance is most useful—as, for instance, in all cases in which some given but not exactly defined quantity of the bottle's contents is to be used—the quantity to 100 be discharged at one time may thus be measured with sufficient accuracy for all practical purposes.

It is a most common practice, in the use of

all sorts of medicines and liquids put into the market by the trade, to have no more accurately defined directions for the use of the contents of the bottle by the patient or user than that it is to be taken by the tea or table spoonful or wine-glassful, &c.; and as all the designated measuring implements or receptacles vary considerably in capacity in the different makes of spoons and glasses, it follows

5 that even though the measuring-receptacle *e*, when used as herein described, may not always contain precisely the same quantity, it will serve to perform the measuring of doses to be taken with quite as much, if not much 10 greater, precision or uniformity in all cases than is attainable by the present modes of measuring; but in the use of such a bottle or contrivance as that herein shown and described no spoon, glass, or other separate implement or utensil need be used; and even in 15 the dark most persons could, by the sense of feeling only, manipulate the bottle so as to properly supply the receptacle *e* with the right or designed quantity of the bottle's contents, as shown at Fig. 3, and could then extract the cork and drink only the portion of liquid contained in said portion *e*, were it desired to thus take or use the liquid.

If it be desired to measure and pour out the 20 contents into another utensil—as, for instance, in order to mix the liquid with water or some other substance—the cork *C* may be withdrawn while the bottle is in position seen at Fig. 3, and the bottle then tipped into the position 25 shown at Fig. 4, when, as illustrated by the last-named figure, all the liquid contained at *e* will run out without the overflow of any of the liquid of chamber *A* into *e*.

If deemed expedient, the neck portion *B* of 30 the bottle may be provided with the supplemental device of indicating-lines or a scale of marks, either as illustrated by the dotted lines at Fig. 1 or by those at Fig. 3, (or with any other sort of gage-marks or devices;) but in 35 practice, for most purposes, the proper predetermination of the size and shape of the receptacle portion *e* (so as to hold either a tea or table spoonful or other prescribed quantity) will, I presume, render the novel bottle contrivance capable of answering well its intended 40 uses.

Of course the design and all the details of construction of my novel dose-measuring bottle may be considerably varied, in the judgment 45 of the maker and user of the contrivance, and according to circumstances to be considered, without materially departing from the principle of construction peculiar to my invention, the gist of which is in having the bottle made 50 with some sort of auxiliary chamber or receptacle-like device so relatively arranged with the main or body portion of the bottle and its mouth that when the bottle shall be turned into a certain position the liquid will 55 flow into said auxiliary receptacle, and when

turned into another position will be divided or separately held in both the said receptacle and the main or body portion of the bottle, and may be discharged from the former without the discharge of any portion of the contents of the latter.

At Fig. 5 I have shown a modification of my invention, in which there is no bulging receptacle in the neck portion *f*, which is placed one-sided, (as is common in some bottles, such as small ink-bottles, now made,) but in which a sort of partition, *h*, divides the body of the bottle into two compartments, *i* and *j*, and is perforated at *x*. In this form of my invention, by holding the bottle in a substantially horizontal position, with its shorter side downmost, and then turning it axially to bring the longer side or line of the body downmost, the chambers *i* and *j* will stand full to the same level, but have the contents of each separated 70 from that of the other by the partition *h*, (assuming, of course, always that the bottle be not so nearly full that in the last-named position of it the liquid will be at a level such as to flow through the aperture *x* of the partition,) 75 and then, by inclining the bottle to an oblique position, as seen at Fig. 5, so as to permit the removal of the cork *l* without spilling any liquid, a quantity of liquid will be measured 80 in and can separately be run out of the compartment *i* without discharging any portion of the contents of *j*.

At Fig. 6 is shown still another modification, in which the bottle has its interior divided into two compartments, *m* and *n*, by a solid partition, *o*, and is provided or formed with a sort of tubular passage or communication (*s*) between the compartments. In this form of contrivance the measuring and separate discharge of the desired quantity of the 90 liquid contents of the bottle may be accomplished by a manipulation of the bottle about similar to that explained in reference to the modification shown at Fig. 5.

What I claim as of my invention, and desire 100 to secure by Letters Patent, without restriction to any mere matters of form or precise arrangement of the devices shown and described, is—

A bottle or liquid-receptacle having its main 115 chamber or receptacle supplemented with a measuring receptacle or chamber, into which latter the liquid contents of the bottle may be made to flow, and from which the contained liquid can be discharged through the mouth of 120 the bottle without discharging from the main receptacle of the bottle any portion of its contents.

In testimony whereof I have hereunto set my hand this 15th day of December, 1880

JAMES M. DODGE.

In presence of—

JULIUS GOLDZIER,
W. D. EWART.
